George A. Rockwell ATTORNEY.

UNITED STATES PATENT OFFICE.

BENJAMIN B. HATCH, OF BOSTON, MASSACHUSETTS.

SIGNAL SYSTEM.

1,168,630.

Specification of Letters Patent. Patented Jan. 18, 1916.

Application filed July 16, 1915. Serial No. 40,330.

To all whom it may concern:

Be it known that I, BENJAMIN B. HATCH, of Boston, in the county of Suffolk and State of Massachusetts, have invented a new and useful Signal System, of which the following is a specification.

My invention relates to signal systems usually employed for fire alarm or emergency signals of which an example is disclosed in my Patent No. 917,061 dated April 6, 1909, and my invention herein disclosed differs chiefly from that of said patent in the provision of a plurality of indicators instead of the single indicator I of said patent and this difference requires reorganization of the system of said patent and accomplishes important new results in the way of efficiency and accuracy.

In the drawing I show a diagram of my new system fully described below.

My system may be connected to any suitable box, such, for example, as that shown in said patent and therefore it is unnecessary herein to disclose such parts as the boxes and door.

Reference character a^2 represents the pivot of the door of the box.

Pivotedly mounted at a^6 is an arm a^7 available at the proper time to the operator and constituting the main signal circuit operating member. Arm a^7 has a projection into the path of which a stud a^{13} on arm a^{14} normally projects. The arm a^{14} is the local signal circuit operating member and is suitably pivotally mounted. When an alarm is to be given the member a^7 is depressed and then released. The downward movement of member a^7 carries member a^{14} with it thereby setting the local signal box in operation, a suitable spring or springs (not shown) serving to restore the members a^{14} and a^7 to normal position again.

The hub of the member a^7 is made with a pair of lugs a^{16} which embrace a lip a^{17} on an arm a^{18} fixed to a shaft a^{19} . The other end of the arm a^{18} carries an arm a^{20} provided with a stud a^{21} coöperating with one of the contacts of a switch a^{22} . The switch a^{22} is in the main signal circuit so that when member a^7 is depressed as above described the lugs a^{16} acting through arm a^{18} , shaft a^{19} , arm a^{20} and stud a^{21} serve to close the switch a^{22} and thereby operate the main signal circuit. It will thus be seen that when

the member a^7 is operated with the door in its closed position the member a^{14} is also operated and therefore both the main signal circuit and the local signal circuit are operated. The pintle a^2 on which the door is hinged and which turns with said door has fixed to it a bolt in the form of a disk a^{23} made with a notch which is in the path of arm a^{18} so long as the door is closed so that the arm a^{18} is then free to be operated by the lugs a^{16} on the hub of member a^7 . Whenever, however, the door is opened or not entirely closed the notch is not in the path of the arm a^{18} and therefore the disk a^{23} locks the arm a^{18} against operation. When the door is swung open on pintle a^2 lugs a^{16} are carried out of coöperative relation with the lip a^{17} so that movement of the member a^7 will not tend to operate the arm a^{18} , all as described in said patent. The disk a^{23} is also made with a notch a^{25} coöperating with an arm of a bell crank a^{26} pivoted at a^{27} . The other arm of the bell crank a^{26} carries a stud a^{28} coöperating with one of the spring members of a switch a^{29} . When the door is in its closed position the notch a^{25} permits a spring a^{30} to hold the bell crank a^{26} in such position that the switch a^{29} is closed but when the door is open and the notch a^{25} is shifted toward the arm of the bell crank a^{26} the disk a^{23} acts as a cam to operate the bell crank a^{26} and thereby open the switch a^{29} . The switch a^{29} is in the disarrangement signal or indicator circuit and it will therefore be seen that when the door is opened this indicator circuit will be operated.

The switches a^{22} and a^{29} are in the circuits described below.

As herein shown the system when in normal condition includes two normally closed disarrangement circuits each having a separate battery of its own; and automatic means is provided through which an indicator or signal is operated by the battery of one of those circuits when the battery of the other circuit is depleted or when the other circuit is not in normal condition and another signal or indicator is operated by the battery of the other circuit when the battery of the first mentioned circuit is depleted or when the first-mentioned circuit is not in normal condition. One of these circuits is traced as follows:—From one pole of the main battery Z through wires c , and c'

to one of the usual pair contacts c^{11} , c^{12} at the upper station of the building, from the contact c^{11} through wires c^2 and c^3 to the contact c^{12} of the next station. From the 5 lower station through wire c^4 ; a magnet Y, and wire c^5 , to a contact c^{13} that co-operates with the contact c^{12} of the lower station, from contact c^{13} of the lower station through wire c^6 to the contact c^{13} of the next station 10 and so on to the upper station. From the upper station this circuit continues through wire c^7 , to the usual releasing magnet g of the signal or gong G of the upper station and thence through wire c^8 to the releasing magnet g of the next station, and from the releasing magnet g of the lower station through wires c^9 and c^{10} back to the other pole of battery Z. The magnet Y normally holds its armature y out of engagement 15 with a contact y' but as will now be clear, if the circuit just traced is opened at any point or if the battery Z becomes exhausted then the armature y will drop into engagement with contact y' thereby closing an indicator circuit which is traced as follows: 20 From one pole of a supplemental battery Z' through a wire b to contact y' , through armature y , wire y^2 ; an indicator or signal D and wires y^3 and c^{10} back to the battery Z'. The other normally closed dis- 25 arrangement circuit is traced as follows:— From battery Z' through wires b and b' to a magnet X; through wire b^2 , switch a^{29} , and wire b^3 to the usual detector switch g' of the lower station, said switch being controlled according to the condition of the operating spring of the gong of that station as usual. From this switch g' the circuit continues through wire b^4 , switch a^{29} , and wire b^5 to the detector switch g' of the next station 30 and so on to the switch g' of the upper station. The switch g' of the upper station is connected by a wire b^6 with one of the contacts of the switch a^{22} of said station whereof the other contact, as described above, is connected with wires c and c' . From switch a^{22} the circuit continues through wire b^7 to one of the contacts of the switch a^{22} of the next station whereof the 35 other contact is connected with wires c^2 and c^3 . The switch a^{22} of the lower station is connected by a wire b^8 with one end of the coil of the usual trip magnet W which controls the mechanism, not shown, through 40 which the alarm signal is transmitted to the fire department. The other end of the coil of magnet W is connected by a wire b^9 with the wire c^{10} leading back to battery Z'. The magnet X is, as will now be clear, normally energized and therefore holds its armature x out of engagement with a contact x' . When, however, the circuit just described is opened at any point magnet X is de-energized and drops its armature on to contact x' thereby closing a circuit that is 45

traced as follows:—From battery Z through a wire x^2 , armature x , wire y^4 , indicator E and wires y^3 and c^{10} back to the battery Z.

When the door of any one of the boxes is opened the bell crank a^{28} opens switch a^{29} of that box and thereby operates indicator E. If the member a^7 of any one of the boxes is operated, say, for example, the member a^7 of the station shown at the top of the drawing, then a circuit is closed through the trip magnet W which is traced as follows:— From battery Z through wire c to the lower contact of switch a^{22} of said station and from that contact through the middle contact of said switch, wires b^7 and b^8 , magnet W, and wires b^9 and c^{10} back to the battery Z. The lifting of the armature of magnet W acts as usual to release the mechanism, now shown, which transmits the fire alarm signal to the fire department. As explained above, if a^7 is operated while the door of the box is closed, it operates the member a^{14} and thereby sets the local signal box in operation. This box is constructed as usual with a spring driven wheel c^{14} which operates the contact c^{12} to make and break connection between c^{12} and c^{13} and thereby operate the local signal circuit, or in other words the circuit of the gongs G. This circuit is traced as follows:—From the battery Z through wires c and c' to contact c^{12} , contact c^{13} , wire c^7 , the magnet g of the gong of the upper station, wire c^8 , the magnet g of the gong of the next station. At the lower station the circuit continues from the magnet g through wires c^9 and c^{10} back to battery Z. Thus it will be seen that while the door of any one of the boxes is open the indicator E gives a continuous signal, in addition to which if the member a^{14} of that box is operated the gongs G are caused to operate and the indicator D gives an intermittent signal coincident with the operation of gongs G; and also that when the door is not opened and the member a^7 operated then the indicator E gives a continuous signal until member a^7 is released, whereupon indicator D is operated intermittently to give a fire alarm as well as the gongs G.

The advantage of having two indicators is that no tapping of batteries between outside terminals is necessary and also there may be two separate sounds, said sounds indicating which division of the circuit is out of order, for example, a bell like a sleigh bell gives indication of trouble in the local circuit such as run down springs or an open door or an auxiliary box run down or broken connections of any sort while a bell like a cow bell gives indication that the main battery circuit furnishing energy to gongs or signal boxes is out of order.

What I claim is:

1. In a system of the character described the combination of a plurality of signal cir- 139

cuits; a source of power for each of said circuits; indicating means in each circuit; means controlled by the source of power of one of said circuits for operating the indicating means of the remaining circuits.

2. In a system of the character described the combination of a plurality of signal circuits; a source of power for each of said circuits; indicating means in each circuit; means controlled by the source of power of each one of said circuits for operating the indicating means of the remaining circuits.

3. In a system of the character described the combination of two signal circuits; a source of power for each circuit; indicating means in each circuit; and means controlled by, but having a source of power independent of, the source of power of one circuit for operating the indicating means in the other circuit.

4. In a system of the character described

the combination of two signal circuits; a source of power for each circuit; indicating means in each circuit; and means controlled by, but having a source of power independent of, the source of power of each circuit for operating the indicating means in the other circuit.

5. In a system of the character described the combination of two signal circuits; a source of power for each circuit; and two indicators, each controlled by one of said sources of power but operated by the other sources of power.

6. In a system of the character described the combination of two signal circuits; a source of power for each circuit; indicating means in each circuit; and means controlled by the source of power of each one of said circuits for operating the indicating means of the other of said circuits.

BENJAMIN B. HATCH.
